AUTOMOBILE THEFT ALARM

Filed July 20, 1929

FIG. 1

UNITED STATES PATENT OFFICE

JOSEPH BARBECK, OF CLEVELAND, OHIO

AUTOMOBILE THEFT ALARM

Application filed July 20, 1929. Serial No. 379,687.

My invention pertains to an automobile theft alarm and more particularly to an appliance mainly hidden from ordinary observation and adapted to sound the alarm during any unauthorized driving of the vehicle.

One object of my invention is to provide an appliance which is applicable to any make of car, which is readily attached as an accessory without interference with any other standard operating part of the vehicle, which is adequately economical of manufacture and the operation of which may be readily controlled by lock mechanism.

It is to be realized that the scope of my invention comprehends many equivalent constructions. The showing of the drawing and the particular description are merely specific exemplifications of a plurality of mechanical embodiments and arrangements.

Adverting to the drawing:

Figure 1 is a side elevation of an automobile, a middle portion being shown as a fragmentary section to disclose one exemplifying location of an appliance embodying the principles of my invention.

Figure 2 is an enlarged vertical section on line 2—2 of Figure 1.

Figure 3 is a plan section on line 3—3 of Figure 2 showing in full and dotted lines the functioning and inutile positions respectively of one cooperating displaceable element.

An automobile 1 includes in its driving mechanism the conventional propeller shaft 2 located below the floor 3 of the vehicle. The forward foot board of the floor 3 is provided just ahead of the front seat with an opening 4 in which is mounted a hollow casing 5 of any standard lock mechanism. An annular flange 6, carried by the casing 5, is secured to the top of the flooring by means of screws 7. Fitted in the casing 5 is a plunger 8 adapted to be turned by use of the proper key 9. It should be understood that a combination lock may be substituted for the key control if desired.

The lower end of the plunger 8 carries a transverse pin 10 on which is pivotally mounted a double arm rock lever. Its one

arm 11, when in its functioning position, as shown in Figure 2 and in full lines in Figure 3, projects toward the propeller shaft 2. Its other arm 12, as shown in Figure 2, projects in an opposite direction and has attached to it in any appropriate manner a resilient extension 13 which carries on its extremity a weight or hammer 14. A spring 15 connects the arm 11 with an ear formed on the near side of the plunger 8 and serves to exert an upward pull for a purpose to be hereinafter explained.

Attached in a depending position to the underside of the flooring 3, by means of bolts 16, is a bracket 17, the lower end of which suitably carries a bell 18 in a position to be struck by the hammer 14 though normally out of contact therewith.

It is preferable, not only as a protection against interference with my alarm mechanism, but also to protect it against dust, to provide a housing for the operating mechanism of my invention. I have disclosed a composite housing of quadrilateral form including an upward division 19 outwardly flanged around its top at 20 and confining a gasket 21 against the lower side of the flooring. A lower complementary division 22 of the housing likewise has its upper end outwardly flanged at 23 and such flange is opposed to another flange 24 around the lower end of the upper division 19. Between the flanges 23 and 24 is interposed a sealing gasket 25. The two divisions 19 and 22 of the housing are secured to each other and firmly suspended from the flooring by a series of four bolts 26 having their heads 27 abutting the lower side of the flange 23 and provided in appropriate countersinks formed in the upper surface of the floor with nuts 28.

A shaft 2 is enveloped by two coacting members 29 and 30 each provided with diametrically opposite flanges through which are passed bolts 31 adapted to effect a clamping action of the members 29 and 30 upon the shaft so that they will rotate therewith in the direction indicated by the arrow in Figure 2. One of the flanges, as illustrated one of the two formed on the member 30, is lengthened somewhat at 32 to overhang the flange on the

member 29 which is opposed to it. The member 30 is clamped to the shaft 2 within the composite housing and in such a position that its extension 32 is adapted during its orbital movement to impinge against the free end of the arm 11 and so as intermittently (one for each rotation of the shaft 2) to depress the arm 11 against the action of the spring 15 when the parts are in the position shown in Figure 2 and in full line in Figure 3. Presently, the extension 32 will slip past the extremity of the arm 11 to release it whereupon the spring 15 suddenly pulls it up against a stop 33 and such action causes the hammer 14 to tap the bell 18. As will be readily understood, the bell 18 will be sounded with each revolution of the shaft. A covering plate 34 may be attached to the floor to hinder unauthorized access to the screws 7 and nuts 28.

When the owner of the automobile is himself to drive the car he will insert his key 9 and turn the plunger 8 through an angle of 90° to the position in which it appears in dotted lines in Figure 3, thereby simultaneously displacing the free extremity of the arm 11 beyond the path of orbital movement of the extension 32 and likewise removing the hammer 14 from proximity to the bell 18.

I claim:—

1. In an automobile theft alarm, the combination of a propeller shaft, a projection carried by said shaft, a bell, a resilient hammer pivotally arranged to strike said bell and to be actuated by said projection and lock mechanism for turning the pivot of said hammer to shift it beyond the orbital path of movement of said projection.

2. In an automobile theft alarm, the combination of a propeller shaft, a projection carried by said shaft, a bell, a lock-controlled turnable member having a transverse extension, a rock lever pivotally mounted on said extension, said lever being adapted to strike said bell and to be actuated by said projection.

3. In an appliance of the character described, the combination of a rotary driving member, a box enclosing a section of said member, a bell in said box, and a double armed lever pivotally mounted in said box, a composite clamp on said shaft including a projection adapted to impinge against one arm of said lever to shove it through a predetermined arc at every rotation of said shaft, the other arm being adapted to strike said bell.

4. In an appliance of the character described, the combination of a vehicle fixture, a box attached to said fixture and enclosing a section of said shaft, a lock-controlled member turnably mounted in said fixture and projecting into said box, a bell in said box, a lever movably mounted on said member, said shaft carrying a projection adapt-

ed orbitally to impinge and actuate said lever preparatory to having it strike the bell whenever its position permits as determined by the selective position of said lock member.

Signed by me, this 9th day of July, 1929.
JOSEPH BARBECK.
